CLAIM

The ornamental design for a spotlight, as shown and described.

DESCRIPTION

FIG. 1 is a front perspective view of a spotlight showing my design.

FIG. 2 is a rear perspective view of the spotlight in FIG. 1.

FIG. 3 is a front elevation view of the spotlight in FIG. 1.

FIG. 4 is a rear elevation view of the spotlight in FIG. 1.

FIG. 5 is a left side elevation view of the spotlight in FIG. 1.

FIG. 6 is a right side elevation view of the spotlight in FIG. 1.

FIG. 7 is a top plan view of the spotlight in FIG. 1.

FIG. 8 is a bottom plan view of the spotlight in FIG. 1; and, FIG. 9 is an enlarged view of a portion of the spotlight labeled 9 in FIG. 2.

The dash-dash broken lines illustrate portions of the spotlight. The dash-dot broken lines represent the boundary of the enlarged view. The broken lines form no part of the claimed design.

1 Claim, 9 Drawing Sheets
